UNITED STATES PATENT OFFICE.

LEWIS GRANGER, OF ARMADA, MICHIGAN.

CLOTH-MEASURING MACHINE.

SPECIFICATION forming part of Letters Patent No. 309,053, dated December 9, 1884.

Application filed July 1, 1884. (No model.)

To all whom it may concern:

Be it known that I, LEWIS GRANGER, a citizen of the United States, and a resident of Armada, in the county of Macomb and State of Michigan, have invented certain new and useful Improvements in Cloth-Measuring Machines; and I do hereby declare that the following is a full, clear, and exact description of the invention, which will enable others skilled in the art to which it appertains to make and use the same, reference being had to the accompanying drawings, which form a part of this specification.

This invention relates to cloth-measuring machines intended especially for the use of retail dry-goods merchants; and it has for its object to produce a machine which shall possess superior advantages in point of simplicity, durability, and general efficiency, and which may under all circumstances be relied upon to measure and register correctly.

To this end it consists in the improved construction and arrangement of parts, which will be hereinafter fully described, and particularly pointed out in the claim.

In the drawings hereto annexed, Figure 1 is a perspective view of the machine complete and in position for operation. Fig. 2 is an end view. Fig. 3 is a detail view of one of the adjustable cloth-board holders, and Fig. 4 is a detail view of the gage and a portion of the screw upon which it is mounted.

The same letters refer to the same parts in all the figures.

A in the drawings designates a suitable rectangular base-frame, the ends of which are provided with centrally-located posts or uprights B B, the upper ends of which have slots C C, in which are mounted the cloth-roller D and tension-roller E, both of which have journals or trunnions F, and the former of which is provided with a handle, G, by means of which it may be conveniently revolved in operation. The posts or uprights B B are strengthened by means of metallic braces H H, which are connected in any suitable manner to the ends of the base-frame.

Journaled in or between the uprights B B, a short distance below the cloth-roller, is a rod, I, which is screw-threaded for the greater part of its length, having from twelve to sixteen threads to the inch. One end of the said rod

carries a friction-roller, J, bearing against the under side of the cloth-roller, so that when the latter revolves a rotary motion shall be communicated to the said screw-threaded rod. 55

K is a cross-piece or girt connecting the uprights B B a short distance below the screw-threaded rod, and serving not only as a brace, but also as a register or indicator, it being provided on each side with a properly graduated scale, L.

M is a gage or pointer, (shown in detail in Fig. 4 of the drawings, and consisting, preferably, of a thin plate of sheet metal,) having 65 at its upper end an oblong slot, N, by which it is suspended upon the screw I, and provided at its lower end with fingers or pointers O O, straddling the cross-piece K, and indicating upon the scales of the same the position of the 70 gage.

One of the side pieces, P, of the base-frame is provided with a cloth-board-holding device comprising two uprights, Q R, the former of which is stationary, and provided with a crank-shaft, S, having at its inner end a cross-piece, T, provided with sharp points or prongs U, to enter one end of the board. Upright R slides upon the frame-piece, and is adjustable by means of a set-screw or clamping device, V, of suitable construction. It has at its upper end a centering-shaft, W, which may be provided with a crank, X. At the other side of the frame of the machine are arranged two stationary uprights, Y Y, supporting a crank-shaft, Z, on which is mounted a stationary reel or winder, A², which is provided with four wings, as shown. This construction is deemed preferable, because it enables the cloth to be wound more rapidly, 85 evenly, and accurately than when an ordinary board is used.

From the foregoing description, taken in connection with the drawings hereto annexed, the operation and advantages of this invention will be readily understood. The cloth-board having been placed in its holding device, the end of the cloth to be measured is introduced between the rollers D E, between which it will be caused to pass by revolving the former. If the material is to be returned to the cloth-board, I wind it upon the reel A²; if not, this may be dispensed with. It is evident that, the diameter of the cloth-roller be-

ing known, as well as that of the friction-pulley, and the number of threads to the inch of the screw-threaded rod, the gage may be easily laid out, so as to indicate correctly the 5 number of yards of goods passing between the rollers. As the feed-screw revolves, the gage M, which rests in only one thread thereof, will travel forward, thus showing upon the scale the number of yards passing through the ma-
chine.

It is obvious that this invention is susceptible of various modifications, and I desire to have it understood that I reserve to myself the right to any such changes as may be made 15 without departing from the spirit of my invention.

Having thus described my invention, I claim and desire to secure by Letters Patent of the United States—

In a cloth-measuring machine constructed 20 substantially as set forth, the combination, with the cloth-roller, the scale, and the feed-screw having a friction-pulley engaging the cloth-roller, of the herein-described gage or pointer, consisting of a thin plate of sheet 25 metal having at its upper end an oblong slot, by which it is mounted loosely in a single thread of the feed-screw, and provided at its lower end with fingers or pointers straddling the scale-bar, substantially as set forth.

In testimony that I claim the foregoing as my own I have hereunto affixed my signature in presence of two witnesses.

LEWIS GRANGER. 30

Witnesses:

WILLIAM MAY,
VICTOR T. LEMKE.
